UNITED STATES PATENT OFFICE.

EMMA BROWN, OF PATERSON, NEW JERSEY.

DESIGN FOR A KNITTED FABRIC.

No. 39,999.

Specification for Design.

Patented May 18, 1909.

Application filed February 23, 1909. Serial No. 479,662. Term of patent 7 years.

To all whom it may concern:

Be it known that I, EMMA BROWN, a citizen of the United States, residing in Paterson, Passaic county, New Jersey, have invented a new, original, and ornamental Design for a Knitted Fabric, of which the following is a specification, reference being had to the accompanying drawing, forming part hereof.

The drawing shows a plan of a piece of the fabric.

The fabric is knitted in alternating stripes

a and *b*, the mesh of the stripes *a* being larger than those of the stripes *b*. The stripes *a* and *b* are connected by groups of filaments *d*, each group converging from one stripe *b* to the adjoining stripe *a*.

I claim—

The ornamental design for a knitted fabric, as shown and described.

EMMA BROWN.
